UNITED STATES PATENT OFFICE.

JOHN TAYLOR, OF POCATELLO, IDAHO.

STEAM GENERATOR.

1,427,176.

Specification of Letters Patent. Patented Aug. 29, 1922.

Application filed March 20, 1920. Serial No. 367,334.

To all whom it may concern:

Be it known that I, JOHN TAYLOR, a citizen of the United States of America, residing at Pocatello, in the county of Bannock 5 and State of Idaho, have invented certain new and useful Improvements in Steam Generators, of which the following is a specification.

This invention relates to steam generators 10 and it has for its object the provision of an improved device of this character constructed to burn fine fuel such as powdered coal dust and to generate steam at a minimum expense and with maximum efficiency.

15 Broadly stated the device comprises a steam boiler consisting of suitable water containing chambers or castings, a combustion chamber into which powdered coal dust or like fine fuel may be delivered tangentially under the influence of forced draft created by a fan, said fan in turn being driven by a turbine that is supplied with steam from the boiler. The device further includes means for hand firing of the boiler 20 which means may be employed either in moderate weather, in emergencies, or for initially getting up sufficient steam to start the turbine in operation.

The device further includes means for 30 automatically returning the water of condensation to the boiler.

Further objects and advantages of the invention will be set forth in the detailed description which follows.

35 In the accompanying drawing

Figure 1 is a transverse vertical sectional view of the boiler upon line 1—1 of Fig. 2 with the various pipe connections shown in elevation;

40 Fig. 2 is a longitudinal sectional view of the boiler upon line 2—2 of Fig. 1;

Fig. 3 is a transverse vertical section upon line 3—3 of Fig. 2;

45 Fig. 4 is a transverse vertical section upon line 4—4 of Fig. 2;

Fig. 5 is a diagrammatic front elevation of the generator;

Fig. 6 is a transverse vertical section upon line 6—6 of Fig. 2; and

50 Fig. 7 is a view partly in elevation and partly in section illustrating a water trap utilized for automatically returning the water of condensation to the boiler.

Like numerals designate corresponding 55 parts throughout the several views.

Referring to the drawing 5 designates a circular combustion chamber having a fire brick lining 6. This combustion chamber is partially embraced by a water jacket 7 formed as a part of the water space within a casting 8. A fuel supply pipe 9 is divided into the branches 10 and 11. The branch 10 discharges tangentially at 12 into the combustion chamber. The branch 11 discharges tangentially into the combustion chamber at 13. An opening 14 formed in the bottom of the combustion chamber serves to discharge the ash clinker and slag into an ash chamber 15 formed within a block 16 underneath the combustion chamber. The chamber 15 in turn discharges through an opening 17 at its bottom. This opening aligns with an opening 18 that constitutes the entrance to an ash pit 19. It is to be noted that the path of the incoming fuel through branch 11 traverses the path of the material that is falling from the opening 17 into the opening 18. Slag and heavy clinker will be heavy enough to fall into the chamber 19 but incandescent, partially consumed cinders which are comparatively light would be returned to the combustion chamber 5 and entirely consumed. I preferably provide a dumping plate 20 beneath the opening 14 and the shaft 21 upon which this dumping plate is mounted is extended to the exterior of the furnace and there provided with a counter weight 22 (see Figs. 2 and 5).

Powdered coal dust or other fine fuel is 30 delivered from a bin or hopper 24 into the casing of a blast fan 25. This fan is in turn actuated by a steam driven turbine 26 that is supplied with steam from the steam space in the boiler, indicated at 27, through 35 a pipe 28. The exhaust steam from the turbine is delivered through an exhaust pipe 29 into a separation tank 30. The powdered coal is delivered from the bin 24 into the fan casing 25 through a pipe 31 40 in which a worm conveyer, 31^a is disposed. The shaft of this worm conveyer is indicated at 32 and is driven by a worm gearing 33 from a shaft 34. This feed mechanism has been made the subject matter of a separate application Serial Number 302,330 filed on the 6th day of June 1919, Patent No. 1,373,776 of April 5th 1921, and consequently needs no detailed description here. 45

From the foregoing description it will 50

be readily understood that the powdered fuel being delivered tangentially into the circular combustion chamber 5 is thoroughly and homogeneously mixed with the air delivered 5 from the fan and consumed, and that the cinders are returned to the combustion chamber as set forth until they are entirely consumed while the slag and clinker are delivered into the chamber 19. The products 10 of combustion from the combustion chamber 5 are delivered, in the direction of arrows A, through an axial opening 35 formed in the rear wall of said combustion chamber, into a cinder trap chamber 36 15 formed in the block of fire brick 37 and in the fire brick cap 38. A conduit 32' leads from the bottom of the chamber 36 to the interior of the block 16 so that such light cinders as fall therethrough will be caught 20 by the blast from the branch 11 of the feed pipe while any heavier particles finding their way thereto will be discharged into the ash pit 19 (see Fig. 2). From the cinder trap chamber 36 the products of 25 combustion pass laterally through an opening 39 over into the combustion chamber 40 of the hand fired side of the furnace (see arrows b). This chamber is provided with grates 41 designed to hold fine fuel and 30 consisting of a plurality of longitudinally extending grate bars of inverted L-shape in cross section that are disposed along the inclined faces 42 of triangular plates 43, said plates in turn being pivotally mounted 35 at 44 upon brackets 45 so that they may be given a slight rocking motion if desired. The combustion chamber 40 is provided with a fire brick cap 45 and is in communication through a natural draft opening 46 with a 40 chamber 47 having a doorway 48 that is closed by door 49.

By referring to Fig. 4 it will be seen that the sections 50 of the furnace, of which there be as many as desired, consist of cast- 45 ing shaped to form steam spaces 51, side water legs 52 and 53, bottom water spaces 54 and hollow water receiving partition walls 55, one of these partition walls constituting one of the sides of the combustion 50 chamber 40. These castings further comprise horizontal water legs 56 and connecting vertical water legs 57. The products of combustion pass, as stated, through the opening 39 into the combustion chamber 40, thence rearwardly and over the partition wall 55, (see arrows c) the products of combustion pass thence rearwardly over and around the various water legs of the sections 55 50 and between the water legs 59 of sections 60 of which there may be as many as desired. These sections comprise the steam spaces 61, side water legs 62 and 63 and bottom water spaces 64. The water spaces of the several sections are in communication 65 through openings 65 and these sections are tied together by longitudinally extending tie rods 66 as is common in furnace constructions. The rear cover plate 67 of the generator is preferably provided with a clean-out opening 68 that is closed by a door 69. A flue 70 leads from this cover plate through which the products of combustion finally escape. A bracket 71 supports the tank 30 and also supports the casing 72 of a valve hereinafter described. A pipe 73 leads from the tank 30 to the valve casing while a pipe 74 leads from said valve casing to the water space within the boiler. A pipe 75 leads from the tank 30 to the valve casing 72. At the valve casing the pipe 75 has communication with a port 76 and the pipe 73 has communication with a port 77. A valve plug 78 is mounted to turn in the casing 74 and is provided with two longitudinally extending ports, 79 and 80. At the end of the valve plug 78 the port 80 communicates with the pipe 81 which leads to a tank 82 while at the end of port 79 a pipe 83 is connected to the valve plug and leads to the tank 82, it being understood that the tank 82, pipe 83, pipe 81 and valve plug 78 all move together. A counter weight 84 is connected by an arm 85 with the valve plug 78 and moves with the other members named.

With the parts in the position indicated in Fig. 7 water of condensation may flow from the tank 30 through pipe 75, port 76, port 80, pipe 81 into the tank 82, any steam or air in said tank being driven out through pipe 83, port 79, port 77 and pipe 73 to the upper part of the tank 30. When, by reason of the accumulation of water of condensation, the tank 82 becomes sufficiently filled with water to overcome the counter weight 84, the tank 82 will descend to the dotted line position. This will move the plug of the valve 78 to bring port 80 into communication with pipe 74 and will bring the port 79 into communication with a port 86 which is connected by a branch 87 with the steam pipe 28. Water may then flow from 82 through pipe 81, port 80 and pipe 74 to the boiler, it being apparent that this movement of the water can take place against the pressure within the boiler because steam pressure will be applied to the top of the tank 82 through pipe 87, port 86, port 79 and pipe 83. This action will continue until the tank 82 is emptied enough to permit the counter weight 84 to return it to its former position.

The tank 30 is connected by a pipe 88 with a T 89 and this T is in turn connected with a branch pipe 90 which leads to a system of radiators in a building to be heated. A pipe 91 connects the T 89 with the outlet of an ordinary automatic blow-off valve 92, the said valve being connected at 93 with the steam space of the boiler.

If the pressure rises above a predetermined degree the automatic blow-off valve will discharge into the pipe 91 and will consequently so increase the pressure in tank 30 5 and exhaust pipe 29 of the turbine as to either slow down said turbine or stop the same. The cutting off of the supply of fuel to the combustion chamber 5 will so diminish the generation of steam as to permit the 10 pressure to return to the desired point. As soon as the automatic valve 92 closes and relieves the back pressure upon the exhaust pipe 29 the turbine will start and the generator will resume operation. The time required 15 for the turbine to resume its operation is very short and the fire brick within the combustion chamber 5 will remain incandescent for a considerable period of time and will immediately ignite the incoming 20 fuel when the turbine resumes its operation. From the foregoing description it will be seen that a simple, compact and highly efficient organization of parts is herein provided for continuously generating steam, for 25 automatically controlling the degree of pressure and for employing powdered coal dust with maximum efficiency.

It is to be understood that the invention is not limited to the precise construction set 30 forth but that it includes within its purview whatever changes fairly come within either the terms or the spirit of the appended claims.

Having described my invention, what I 35 claim is:

1. The combination with a furnace and boiler of a fuel feeding means operated by boiler pressure and means operable upon increase of boiler pressure beyond a predetermined point to admit boiler pressure to the 40 exhaust line of the pressure operated fuel feeding means to retard the same.

2. The combination with a furnace and boiler of a fuel feeding means for the furnace, a steam engine for operating the same, an automatic pressure operated valve opening upon the creation of excess pressure in the boiler and connections between the valve and the exhaust line of the engine through 50 which back pressure is put upon the exhaust line to slow down the engine when the pressure in the boiler exceeds a predetermined degree.

3. The combination with a furnace and boiler of a fuel feeding pipe for the furnace, a fan for creating a blast in said pipe, a source of fuel supply delivering to said fan, an engine operated by steam from said boiler for driving said fan to feed fuel into said 60 pipe, a blow-off valve automatically operable upon the creation of excess pressure in the boiler and connections between said blow-off valve and the exhaust line of the engine, through which back pressure is created in 65 the exhaust line to retard the engine when

the pressure in the boiler exceeds a predetermined degree.

4. In a device of the character described the combination with a substantially circular combustion chamber, of a fuel feeding pipe having two branches, one of said branches discharging directly into said combustion chamber and the other of said branches also discharging into said combustion chamber at a point spaced from the point of discharge of the first named branch and farther about the circumference of said chamber, a block having a chamber therein located beneath the combustion chamber, said chamber of the block being in communication with the bottom of the combustion chamber, an ash pit below the chamber of the block there being a passageway connecting said ash pit with said chamber, the last named branch pipe leading to and from the opposite sides of said passageway so that the blast through said last named pipe is caused to traverse said passageway at right angles thereto, whereby ash and cinders falling from the combustion chamber 90 through said chamber of the block into the ash pit are subjected to the action of the blast passing through said last named branch pipe.

5. In a device of the character described the combination of a circular fine fuel burning combustion chamber and water spaces some of which constitute a water jacket for said combustion chamber, a second combustion chamber lying at one side of the first named combustion chamber, and provided with grates for coal or wood, and a cinder trap in the rear of the first named combustion chamber and communicating with the last named combustion chamber there being a port formed in the rear wall of the first named combustion chamber and communicating with said cinder trap.

6. The combination with a circular combustion chamber having a port for the escape of the products of combustion formed axially in its rear wall, of a fuel supply pipe comprising two branches each of which discharges tangentially into said combustion chamber, an outlet from the combustion chamber between the entrance points of the said two branches thereinto, a hollow block below said outlet, an ash pit disposed below said block, there being a passage connecting the interior of the block with the ash pit, the last named passage being traversed by the blast through one of the branches of the fuel supply pipe.

In testimony whereof I affix my signature in the presence of two witnesses.

JOHN TAYLOR.
